UNITED STATES PATENT OFFICE.

GULIELMUS V. HEIDT, OF GOVERNORS ISLAND, NEW YORK.

DESIGN FOR A HAT NET.

Application filed April 19, 1928. Serial No. 26,380. Term of patent 7 years.

To all whom it may concern:

Be it known that I, GULIELMUS V. HEIDT, a citizen of the United States, residing at Governors Island, in the county of New York and State of New York, have invented a new, original, and ornamental Design for Hat Net, of which the following is a specification, reference being had to the accompanying drawing, forming part thereof.

The figure is a perspective view of the hat net constituting my design, the same being shown as it appears when in use on a hat which is indicated in dot and dash lines.

I claim:

The ornamental design for a hat net as shown and described.

GULIELMUS V. HEIDT.
